COMBINED WASHING BASKET AND DISPENSER FOR TABLEWARE OR THE LIKE

Fosdick Zabriskie, Brooklyn, N.Y., assignor to The Foley-Irish Corporation, Brooklyn, N.Y., a corporation of New York

Application March 4, 1959, Serial No. 54,843

Term of patent 14 years

(Cl. D49—1)

Fig. 1 is a front, perspective view of a combined washing basket and dispenser for tableware or the like showing my new design.

Fig. 2 is a bottom plan view thereof.

Fig. 3 is a side elevational view thereof, on a reduced scale.

The rear and undisclosed end of the combined washing basket and dispenser for tableware or the like are the same in appearance as the front and disclosed end shown in Fig. 1.

I claim:

The ornamental design for a combined washing basket and dispenser for tableware or the like, as shown and described.
